ATTORNEY

UNITED STATES PATENT OFFICE.

MARSHALL C. LEFFERTS, OF NEW YORK, N. Y.

DESIGN FOR A HANDLE FOR RAZORS.

SPECIFICATION forming part of Design No. 24,229, dated April 23, 1895.

Application filed March 25, 1895. Serial No. 543,301. Term of patent 7 years.

To all whom it may concern:

Be it known that I, MARSHALL C. LEFFERTS, a citizen of the United States, residing at the city, county, and State of New York, have invented and produced a new and original Design for Handles for Razors and the Like, of which the following is a specification.

The essential feature of my design resides in the configuration and ornamentation of the handle.

In the drawings, Figure 1 is a side elevation, and Fig. 2 an edge view, of my design.

The general configuration of the handle is curved and articulated, and the surface is provided with transverse irregular grooves 1,

with bordering swells 2, and knot-like figures 3, and irregular depressions 4, which heighten the articulated effect.

The bottom or end 5 of the handle is wedge shaped as shown. 20

I claim—

The design for handles for razors and the like, substantially as herein shown and described.

Signed at the city, county, and State of New York, this 22d day of March, 1895.

MARSHALL C. LEFFERTS.
